INVENTOR

Levi H. Connor
By his Attorney,
Nelson M. Howard

UNITED STATES PATENT OFFICE.

LEWIS H. CONNOR, OF BROOKLINE, MASSACHUSETTS, ASSIGNOR TO UNITED SHOE MANUFACTURING CORPORATION, OF PATERSON, NEW JERSEY, A CORPORATION OF NEW JERSEY.

FASTENING-SUPPLYING APPARATUS.

Application filed April 19, 1926, Serial No. 102,995, and in Germany March 22, 1926.

My invention relates to apparatus for supplying such fastenings as nails to the mechanism by which they are to be utilized, it being particularly directed to organizations in which the fastenings are carried for delivery in a plurality of groups or loads in a holder. A machine of this character is disclosed in Letters Patent of the United States No. 1,325,751, Pope, December 23, 1919, in which machine groups of nails are held in openings in a block supported upon a carriage, and moved thereby to bring successive groups into position for delivery to the driving mechanism of a heel-attaching machine. In many, if not most instances, the conditions of shoe-manufacture are such that not only all the nails of a block are used for succeeding operations, these nails being of the same length, but also that a number of blocks containing nails of such length will be employed without interruption. When this is true, the operator need give but little attention to the nail-supply, merely substituting in the apparatus, without taking time for selection, a fresh block as the supply from each is exhausted. In small shops, however, the run of shoe-sizes may be such that the same length of nail is used for the heelings of but a few pairs of shoes in succession, so that the change of blocks must be frequent, and the order in which the different lengths of nails are called for may be irregular. An object of my invention is to facilitate the supplying of nails under such circumstances, the change of length being made not only easy but accurate, and without danger of displacement of the nails from the blocks or holders during their handling. To achieve this object, I combine with a support for a nail-block, or other device by which fastenings are held in delivering position upon an inserting machine, as a heelers, means arranged to carry a plurality of said devices to present them selectively to the supporting means. The supporting means and carrying means may take the form of traveling carriages, the last-mentioned means furnishing a magazine for supplying the holding devices to the former. The transfer of the devices from the magazine to the supporting means is preferably effected by means mounted upon one of the carriages, as that from which the nails are delivered. In the form of the invention il-

lustrated herein, the magazine-carriage is controlled by the operator, as through the agency of a hand-wheel provided with index means. In the structure of the patent previously referred to, there is a retaining member for the nails in the holder, which retaining member is movable to release said nails, together with an actuating member for causing this movement. To prevent the actuation of the retaining member during transfer of the holding blocks between the carriages, I make the actuating member movable into and out of the path of said retaining member at its rear edge, as by mounting it upon a spindle and governing its position by a handle. 70

One of the several possible embodiments of my invention is illustrated in the accompanying drawings, in which:

Fig. 1 is a top plan view of my improved nail-supplying apparatus in place upon a heel-attaching machine, but a portion of the latter, in horizontal section, being included;

Fig. 2 is a front elevation of the apparatus; and

Fig. 3 is a side elevation, looking from the right of Fig. 1.

Of the heel-attaching machine M, in association with which I have chosen to show the apparatus of the present invention, there appears only a part of the frame 10 and the nail-driving mechanism, including the die-block 12, in the nail-receiving openings 14 of which operate drivers 16 mounted upon the top girt 18 reciprocated by side rods 20. About one of these side rods is mounted an arm 22, carrying a loader-block 24 and arranged to oscillate from a position in which it receives a load of nails to one in which it delivers these to the die-block-openings 14. 90

To furnish successive loads of nails to the loader-block, there may be employed an apparatus of the general character of that appearing in Patent No. 1,325,751, hereinbefore mentioned. This has a frame 26 supported upon the heelers-frame at one side 100 of the die-block, and having at its top a horizontal plate 28, over which is guided for reciprocation a carriage 30 adapted to support, in ways into which it may be slid, a nail-holding block 32. Extending transversely of the block are sets of openings 33 disposed in a series longitudinally of said block, each set being arranged to receive a

group of nails standing with one extremity upon a retaining plate or shutter 34 mounted to slide in ways upon the under side of the block. The number of openings in each set 5 corresponds to the number of nails by which a single heel is to be attached, and of these sets in the longitudinal series there are as many as can be conveniently provided to furnish without change the maximum number 10 of successive loads. At the forward end of the carriage is carried a spring-actuated latch 36 extending normally into the path of the block as it is held in the carriage, this latch serving to correctly locate the block 15 for the initial delivery of a set of nails, and at the same time being movable to permit its introduction or withdrawal. Ratchet mechanism 38 mounted upon the frame 26 and upon the carriage 30, and actuated by 20 the loader-arm 22 when this is swung to nail-receiving position, causes the delivery-carriage to be moved in steps from the rear to the front of the frame, and the sets of delivery-block openings 33 to be brought one 25 by one into registration with a like number of openings 40 formed through the top plate 28 of the frame. After the block has been placed in its supporting carriage at the outer extreme of its path, these are pushed rear- 30 wardly to the opposite end of the plate 28. During this travel, which is in preparation for the delivery of the contained nails, an actuating pin 42, which projects into contact with the rear edge of the shutter, re- 35 tains this shutter against movement. Consequently, the nails are left supported by the frame-plate for delivery, row by row, to the openings 40. In the present instance, the pin 42 is arranged for reciprocation by an 40 eccentric connection to one extremity of a horizontal spindle 44 mounted to rotate upon the plate 28. Normally, as just explained, the pin occupies a position to receive the contact of the plate, but it may be moved 45 away from this by means of a handle 46 which is fixed upon the forward end of the spindle convenient for control by the operator. From the openings 40 the nails are guided by conduits 48 to a foot plate 50, 50 through openings in which they are delivered to the loader-block 24.

Extending transversely across the rear of the frame 26 is a frame-portion 52 provided with ways to receive a carriage 54 furnishing a magazine organized to selectively supply any one of a plurality of nail-blocks to the delivery-carriage 30. The carriage 54 is divided by transverse partitions 56 into spaces, the width of each of which is such 60 as to just receive one of the nail-blocks. At their rear edges, these blocks are held against displacement in the carriage-spaces by stoppins 58, while they are held against accidental forward movement by spring retaining members 60, 60 located at each side of

the spaces upon the partitions 56. The carriage 54 may be moved to bring any block which it carries into alinement with the ways of the delivery-carriage. This I have shown as accomplished by gearing consisting of a rack 62 fixed upon the under side of the carriage 54 and having meshing with it a pinion 64 upon a spindle 66. This spindle is mounted in a horizontal position to turn upon the frame, and has at its forward extremity a hand-wheel 68, through which it may be rotated by the operator. Associated with the hand-wheel is index means, here shown as consisting of depressions 70 formed about the periphery of the wheel, with which depressions co-operates a spring-latch 71 mounted upon the frame. The hand-wheel depressions are so located that when any one of them is engaged by the latch, a particular block-receiving space in the magazine-carriage will be alined with the delivery-carriage 30 in such a manner as to permit the block contained in the space to be moved directly from one carriage into the other. The depressions 70 may have 90 associated with them at 72 designations, each indicating the length of the nails which the block in the corresponding carriage-space is to hold.

To effect the transfer of the blocks between the carriages, there is shown as longitudinally movable in brackets 74 rising from the carriage 30, a horizontal spindle 76. From the rear of this spindle depends an arm 78 having threaded through it, and arranged for co-operation with the end of a block 32, a contact-screw 80 fixed in position by a lock-nut. At the opposite or forward end of the spindle 76 is an upwardly projecting handle 82, while below the handle 100 is an arm 84 fast upon the spindle. Extending rearwardly from the arm 84 in alinement with the screw 80 is a contact-rod 86. A spring 88, extending between the hub of the arm 78 and one of the brackets 74, exerts its 105 tension to hold the spindle normally in its forward relation. Between the opposed ends of the screw 80 and rod 86 is a space just sufficient to receive a nail-block. The length of the spindle 76 and the relation of the elements projecting therefrom to the supporting brackets are such that the arms 78 and 84 may be moved from a position in which they co-operate with opposite ends of a block 110 in the magazine-carriage to one in which such block is seated in the delivery-carriage against the stop 36, and the reverse. Rotation of the spindle permits the arms to be turned to one side and upwardly clear of the blocks, or downwardly for engagement 115 therewith of the contact-screw and rod. This rotation is permitted only when the spindle is in its rearward position, at other times being prevented by a pin 89 projecting into a slot 90 extending longitudinally of the 120 125 130

spindle. When, however, engagement of the arms 78 and 84 with or their release from a block in the magazine is to be effected, a circumferential portion 92 of the slot co-operates with the pin, so that the spindle may be turned through substantially 90 degrees.

In using the apparatus of this invention, the operator places in the magazine-carriage blocks containing all the lengths of nails 10 which it will be necessary to use in heelng the shoes upon which he is to work. Each block preferably contains nails of a length different from those carried by the companion blocks. When a rack of shoes is received, the operator first holds the actuating pin 42 out of the path of the shutter-plate 34 by turning the handle 46, and thrusts the spindle 76 back until the block which has been in previous use is carried into its space 20 in the magazine-carriage. Then the spindle is turned by the handle to raise its arms above the plane of the blocks. The slot-portion 92 at this time receives the pin 88. Then, by manipulation of the hand-wheel 25 68, the operator brings into registration with the latch 71 a notch in the wheel, designated by the length of nail which he wishes first to employ. This aligns the corresponding block in the magazine-carriage with the delivery-carriage 30, the latter being in its forward position. Allowing the arms to return to their normal vertical position, the operator thereupon draws the spindle 76 forward, carrying the selected block from 30 the magazine-carriage to the delivery-carriage, this movement continuing until the block rests against the latch 36 in the latter, which is still at the forward portion of the plate 28. The handle 46 being released, the 40 pin 42 moves to the rear of the shutter 34, and then the operator moves the carriage 30 with the block to the rear of the plate. During this last-mentioned travel, the shutter is held back by the pin 42, so that the lower 45 ends of the block-openings 33 are freed for the delivery of the contained nails, these now resting upon the plate 28. The selected length of nails is thus prepared for delivery, and upon each oscillation of the loader-arm 50 the ratchet mechanism 38 steps the carriage 30 forward, so that successive sets of the block-openings are brought over the plate-openings 40. The loads of nails therefore fall through these openings 40 one by one, 55 and are conducted by the conduits 48 to the openings in the loader-block. The latter transfers them to the nailing mechanism, where they are delivered to the openings 14 of the die-block for driving. After there 60 has been used from the block such a number of the sets of nails of the length first chosen as are necessary to heel the shoes calling for this size, and another length being necessary for succeeding work, the operator 65 proceeds similarly, first transferring the

nail-block back to the magazine-space from which it was taken, and then selecting a new block by means of the hand-wheel 68, and introducing it into the delivery-carriage in the manner just described. As any block becomes emptied, it may be replaced by one which is full. It will be seen that the selection of the size of nail to be used is effected by a conveniently manipulated device so located that its designations may be easily 70 read by the operator. The change of length requires little effort, and in carrying it out, no matter how quickly, there is no danger that the blocks will be dropped and the nails spilled. 75

Having described my invention, what I claim as new and desire to secure by Letters Patent of the United States is:

1. In a fastening-supplying apparatus, means for supporting a fastening-holding device in delivering position, and means arranged to carry a plurality of the holding devices and to present them selectively to the supporting means. 80

2. In a fastening-supplying apparatus, means for supporting a fastening-holding device, means for moving the supporting means to a plurality of delivering positions, and means arranged to carry a plurality of the holding devices and to present any one 90 of them to the supporting means in one of its positions. 95

3. In a nailing machine, nail-driving mechanism, means arranged to carry simultaneously a plurality of loads of nails and 100 to successively deliver these loads to said mechanism, a movable magazine arranged to supply such groups of loads, and means movable to transfer load-carrying means from the magazine for delivery from them. 105

4. In a fastening-supplying apparatus, a traveling carriage arranged to support a fastening-holding device, and a traveling carriage associated therewith and arranged to support a plurality of holding devices for 110 delivery to the associated carriage. 115

5. In a fastening-supplying apparatus, a traveling carriage arranged to support a fastening-holding device, a traveling carriage associated therewith and arranged to support a plurality of holding devices and to be moved by the operator, one of said carriages being arranged to supply a holding device to the other, and means for moving the first-mentioned carriage. 120

6. In a fastening-supplying apparatus, means for supporting a fastening-holding device in delivering position, and a magazine movable to supply holding devices to the supporting means. 125

7. The combination with a heel-attaching machine, of a plurality of nail-block-carriages movable thereon, one of which carriages is arranged to deliver to another. 130

8. The combination with a heel-attaching

machine, of a plurality of nail-block-carriages movable thereon, one of which carriages is arranged to deliver a nail-block to another, and means mounted upon one of the carriages for effecting the delivery.

9. In a nailing machine, nailing mechanism, a carriage arranged to support a nail-holding device for delivery to the nailing mechanism, a magazine arranged to supply nail-holding devices to the carriage, and means mounted upon the carriage for transferring holding devices from the magazine to said carriage.

10. In a heel-attaching machine, nail-driving mechanism, a carriage arranged to support a nail-holder for delivery to the driving mechanism, a magazine-carriage arranged to present a series of nail-holders to the delivery-carriage, and holder-transferring means movable over the delivery-carriage and magazine-carriage.

11. In a heel-attaching machine, nail-driving mechanism, a carriage arranged to support a nail-block for delivery to the driving mechanism, a magazine-carriage arranged to present a series of nail-blocks to the delivery-carriage, and a spindle movable upon the delivery-carriage and having projections for contact with a block in either carriage.

12. In a heel-attaching machine, nail-driving mechanism, a carriage arranged to support a nail-holder for delivery to the driving mechanism, a magazine-carriage arranged to present a series of nail-holders to the delivery-carriage, and a spindle mounted to reciprocate and rotate upon the delivery-carriage and provided with projections arranged to engage a holder in the magazine-carriage and transfer it to the delivery-carriage.

13. In a heel-attaching machine, nail-driving mechanism, a carriage arranged to support a nail-holder for delivery to the driving mechanism, a magazine-carriage arranged to present a series of nail-holders to the delivery-carriage, and a hand-wheel arranged to move the magazine-carriage and being provided with index means.

14. In a heel-attaching machine, nail-driving mechanism, a carriage arranged to support a nail-block for delivery to the driving mechanism, a magazine-carriage arranged to present a series of nail-blocks to the delivery-carriage, a spindle geared to the magazine-carriage, and a hand-wheel fixed to the spindle.

15. The combination with a frame, of nail-conduits mounted therein, a carriage movable upon the frame and having receiving means for a nail-block delivering to the conduits, and a magazine movable transversely to the path of the carriage and provided with a plurality of block-receiving means any one of which may be brought into co-operation with the receiving means upon the carriage.

16. In a nailing machine, nailing mechanism, a nail-holder movable forward for delivery to the nailing mechanism, a movable nail-retaining member associated with the holder, and an actuating member movable into and out of the path of the rear extremity of the retaining member.

17. In a heel-attaching machine, nail-driving mechanism, a nail-block traveling forward to deliver to said mechanism, a nail-retaining plate movable upon the block, and a projection movable into and out of the path of the plate at its rear edge.

18. In a heel-attaching machine, nail-driving mechanism, a traveling nail-block, a nail-retaining plate movable upon the block, a movable spindle extending along the block and provided with a handle, and a projection movable by the spindle and co-operating with the plate.

19. In a heel-attaching machine, nail-driving mechanism, a carriage arranged to support a nail-holder for delivery to the driving mechanism and having movable nail-retaining means, a magazine-carriage arranged to present a series of nail-holders to the delivery-carriage, holder-transferring means movable over the delivery-carriage and magazine-carriage, and movable means for actuating the nail-retaining means.

20. In a heel-attaching machine, nail-driving mechanism, a carriage arranged to support a nail-block for delivery to the driving mechanism and having a movable nail-retaining plate, a magazine-carriage arranged to present a series of nail-blocks to the delivering carriage, means for transferring the blocks from carriage to carriage, a rotatable spindle extending adjacent to the delivering carriage, and a projection normally lying in the path of the retaining plate but movable therefrom by the spindle during the transfer of a block.

In testimony whereof I have signed my name to this specification.

LEWIS H. CONNOR.
